UNITED STATES PATENT OFFICE.

HENRY LEITNER, OF WESTMINSTER, LONDON, AND WILLIAM HERBERT EXLEY, OF WOKING, ENGLAND.

ELECTRIC-ACCUMULATOR PLATE.

1,305,814.

Specification of Letters Patent. Patented June 3, 1919.

Application filed December 16, 1918. Serial No. 266,982.

To all whom it may concern:

Be it known that we, HENRY LEITNER and WILLIAM HERBERT EXLEY, subjects of the King of Great Britain, respectively residing at 3 Victoria street, Westminster, London, England, and "The Rest," Maybury Hill, Woking, Surrey, England, have invented new and useful Improvements in Electric-Accumulator Plates, of which the following is a specification.

Our invention relates to improvements in plates or elements of electric accumulators, of the kind in which lead cores and active material are supported upon a frame of wood. The invention relates more particularly to the lead sulfuric acid bipolar type of plate described in our British specification No. 112956, but the improvements are not confined to plates of this type.

The object of the invention is to provide plates or elements having greater rigidity than the plates or elements heretofore known and also to provide a better contact between the available active material and the lead conductors without appreciably increasing the weight of the latter. By these improvements a lighter, cheaper, non-buckling, non-shortening and rigid element or plate of the bipolar type is obtained, and one which is more suitable for high discharge work, which, as is well known, requires thinner plates than those used for low discharge work.

In the accompanying drawings:—

Figure 1 is an elevation of one form of plate or element having our improvements applied thereto.

Fig. 2 is an edge view thereof.

Fig. 3 is a vertical section on the line 3—3, Fig. 1.

Fig. 4 is an elevation of the parts of the wood support.

Fig. 5 is a view at right angles to Fig. 4.

Fig. 6 is a plan view of the transverse bottom piece of the support of the plate or element; and

Figs. 7 and 8 are an elevation and a plan, respectively, of a modified form of end piece.

Fig. 9 is an elevation of a modified form of support.

Fig. 10 is a plan view thereof.

Fig. 11 is a vertical section on the line 11—11, Fig. 9.

Fig. 12 is a horizontal section on the line 55 12—12 Fig. 9.

Fig. 13 is a view of a detail hereinafter described.

Fig. 14 is an elevation of a portion of a further modified form of support. 60

Fig. 15 is a sectional elevation illustrating a further modification.

Fig. 16 is an end view thereof.

Figs. 16^a, 16^b and 16^c are an elevation, a vertical section and a horizontal section respectively of a modification. 65

Fig. 17 is a horizontal section illustrating a further detail.

Fig. 18 is a vertical section showing a still further detail of construction; and, 70

Figs. 18^a and 18^b are an elevation and a horizontal section of a modification.

Figs. 19, 20 and 21 are an elevation, a plan view and a cross section respectively illustrating the application of the invention to a 75 cell designed for use in torches, hand-lamps and the like.

In one form of our invention as shown in Figs. 1 to 6 *a* represents the support for the conductors and the active material. This 80 support is of wood of a porous nature, which prior to the application of the conductors and active material, is rendered more absorbent, porous and of a spongy resilience,

by being treated, for example, in solutions 85 of hypochlorites and then with dilute sulfuric acid. The support may also be treated with a solution of caustic soda, or potash if found expedient, and this treatment in addition to making the wood more porous, as 90 aforesaid, also extracts all deleterious substances therefrom. The said support is pro-

vided with a series of vertical grooves *b* upon either face of a central web *c* which latter, together with the vertical divisions *d* be- 95

tween the grooves, are made as thin as practicable. The vertical divisions *d* extend beyond the ends of the web *c* and are provided with grooves *e* cut horizontally across the top and bottom of the support, and these 100 grooves are preferably a little wider than the central web *c*. The bottoms of the grooves *e* are spaced away from the ends of the central web *c*, as shown at *f*, and in the web *e* between opposite grooves *b* are a series of 105 holes *g* preferably corresponding in diameter approximately to the width of a groove.

Cross-pieces *h* of wood are notched at *h*¹

to mesh in with the divisions *d* of the support, and these cross-pieces are inserted into the horizontal grooves *e*. The notches *h*¹ are preferably a little wider than the divisions *d* so as to permit a certain amount of lateral movement. This movement is due to the stretching of the wood fiber and expansion of active material. The notched connection of the divisions *d* and cross-pieces *h* 5 prevents undue lateral movement of the support and also prevents any leakage of active material from one side of the support to the other.

The top cross-piece *h* is provided on opposite sides with rabbets or saw cuts *i* of a depth and width corresponding to the dimensions of the collector bars *j* of the positive and negative conductors. The said collector bars, although they cross the tops of 10 the grooves of opposite polarity, are insulated from the active material in these grooves by means of the ledges formed by the rabbets *i*.

The collector bars *j* are united to conductors *k* and terminal lugs *l*, and these parts are preferably stamped, pressed, cut or formed from a sheet or other suitable piece of lead, in such a way, that depending from each collector bar there are a suitable number 25 of streamers *k*. These latter are flattened or otherwise reduced in thickness and twisted into a spiral form for the portion of their lengths which is in contact with the active material, the result being, that increased contact surface is available for the same weight of lead and a stronger connection may be made with the active material. The streamers *k* hang in the grooves *b*, half of the positive streamers extending under 30 the top cross piece *h* and down the negative collector bar side of the central web *c*, and half the negative streamers extend under the top cross-piece and down the positive collector bar side of the web so that each pair 35 of oppositely disposed grooves has either two positive streamers or two negative streamers, as clearly shown in Fig. 3. The free ends of the streamers may be secured by being bent through the space *k'* between the central web and the bottom cross-piece, as 40 shown in Figs. 1 and 3.

The streamers may be given any additional shape or pattern such as the "herring bone," all with the object of further increasing 45 or rendering more effective the available surface. The streamers *k* may also be perforated if desired.

The active material *m* surrounds the streamers *k* and is held in position in the 50 grooves *b* by the twisted streamers *k* and by interlocking with the large holes in the central web *c*.

The streamers *k* instead of being made from the same piece as the collector bars 55 may be formed separately therefrom. For

instance, they may be composed of round wire flattened and twisted and afterward welded or otherwise secured to the collector bars *j*, preferably before the latter are mounted upon the support.

In the modification illustrated in Figs. 9 to 16 the support is built up of a series of vertical strips of wood *d* held together by notched cross-strips *n* having notches *n'* engaging the vertical strips. Where necessary, as would be the case in a long plate or element, additional cross pieces *o* (Fig. 14) may be furnished. This may be inserted transversely through holes in the vertical strips *d* at the requisite intervals, suitable 70 collars or distance pieces being arranged around the said cross-piece as shown at *p* or through the cross-piece as illustrated at *q*. Alternatively the cross-piece may be in two parts viz., a notched part *o* (Fig. 15) and the plain part *o'*, of the holes in the vertical strips being big enough to allow the notched pieces to be inserted, after which the plain pieces are wedged in place to secure the notched pieces in position.

The vertical strips in this form of our invention may be of any convenient cross section preferably a double T or cross shape as shown in Figs. 9, 12 and 14, the said strips being cut away wherever the transverse cross pieces are inserted and the result being that the active material is held in position by both the cross strips and the central inward projections on the vertical pieces, as well as the twisted streamers *k*. It will be understood that in this latter form of our invention, the stretching or lateral expansion of the support as a whole is practically eliminated as the "grain" of the wood in the transverse cross-piece is at right angles to the grain of the wood in the vertical strips, and as the latter are entirely separate units their expansion is local only and readily kept within practical limits by the transverse cross-pieces, which latter are an additional safe-guard against undue lateral expansion.

In lieu of the twisted streamer form of conductor above described, we may make use of a number of grid-like streamers depending from the common collector bars, these streamers being pressed or stamped to form a series of horizontal bars *k''*, half of such horizontal bars being pressed in one direction and the other half being pressed in the opposite direction, as clearly shown in Figs. 16^a, 16^b and 16^c. The portion of the grid covered by the active material is reduced in thickness while the exposed portion is left normal.

With this construction, the grid-like streamers have their free or bottom ends secured to the bottom cross-piece by being inserted in recesses *k'*, Figs. 9 and 11.

In both the aforementioned forms of our

130

invention, we may make the bottom cross-piece of the same width as the divisions *d* as shown at *h*¹⁰ in Figs. 7 and 8, and if desired, we may taper the lower portion of the 5 edges of the divisions *d* and the lower portion of the faces of the bottom cross-piece, as shown in Fig. 11. We may also make the top cross-piece of the same width as the divisions *d* in order to fill up the entire top ends 10 of the vertical grooves with the exception of the spaces necessary to allow the positive and negative conductors to pass. The cross-piece *n* is shown detached, Fig. 13. The spaces which are left unfilled by the conductors 15 may be closed by suitable plugs.

The strips *d* may, as shown in Fig. 17, be made thinner in cross section at the middle than at the edges so that when the strips are assembled to form a plate, the 20 cross section of the space formed between each pair of adjacent strips is of the under-cut shape, that is to say, is larger at the center than at the two faces. By this means the active material, when it is compressed 25 into position on the plate, is effectually held independently of any lock or grip which may arise from the shape of the conductors in which the said active material is embedded.

30 Furthermore, we may curve or under-cut the inward faces of the top and bottom cross-pieces of the support as shown at *r* in Fig. 18, in such a manner that the space formed by them in vertical section is larger 35 at the center than at the two faces, thus imparting an additional locking effect to the active material independently of the conductors *k*.

In some cases, for example, with large 40 plate elements, it may be advisable to make use of a composite support in which the top and bottom cross-pieces, together with the two end strips, are composed of ebonite, celluloid, impregnated teak or other suitable acid resisting material of greater mechanical strength than porous wood, the dividing strips, however, being made of the porous wood.

Furthermore, in practice we find it advantageous 50 to make the vertical strips *d* of the support wider than is actually necessary to hold the active material, as illustrated in Fig. 17, so that when the said strips are assembled to form a support they 55 project laterally beyond the active material, and then act as separators. With this construction, the outer edges of adjacent vertical strips approach each other so that each strip of active material is to all intents 60 and purposes boxed in, whereby any portion of such material which may become dislodged cannot cause a short circuit between neighboring strips.

Free circulation of the electrolyte can be still further insured by cross-cutting the 65 vertical strips with saw cuts or notches *d*¹ extending to, or nearly to, the active material, as shown in Figs. 18^a and 18^b.

Figs. 19, 20 and 21 show the application of the invention to a cell such as is used in 70 connection with torches or the like. In this construction the support is preferably made with notches *s* at each end and strips of wood *t* are forced into the said notches, these strips being the equivalent of the end 75 cross-pieces *h* and *n* above described. In this case the positive and negative terminal lugs *u*, *u*¹ are situated at opposite ends of the support.

Claims:

1. In a plate or element for an electric accumulator, a support comprising a series of strips of porous wood having grooves between the same, active material located in said grooves, conductors embedded in said active material, and end pieces having notches engaging said strips, said notches being wider than the thickness of said strips to permit expansion and contraction of the support and active material. 80

2. A plate as defined in claim 1, in which the strips are thinner at the middle than at the edges, and the end pieces are formed with curved under faces for locking the active material in the grooves. 90

3. A plate as defined in claim 1, in which one of the end pieces is provided with a rabbet, a collector bar engaging said rabbet, and a series of conductors carried by the collector bar and located in said grooves. 100

4. A plate as defined in claim 1, in which the edges of the strips project beyond the active material, so as to entirely isolate the material in one groove from the active material in an adjacent groove. 105

5. An element for electric accumulators comprising a non-conducting support including spaced strips, notched cross-pieces having their notches engaging the strips for securing the strips together, active material 110 located in the space between said strips, and conductors embedded in said active material.

6. The combination with a grooved support having a space near its upper edge, of 115 a collector bar located in one side of said support and carrying a plurality of conductors, one of said conductors extending down one side of the support, another conductor extending through the space at the upper edge of the support and extending down to the other side of the support, and active material surrounding said conductors. 120
